AUXILIARY CONTROL HANDLE FOR SHOVELS

Orville K. Doyle, Fullerton, Calif.

Application May 4, 1953, Serial No. 352,839

4 Claims. (Cl. 294—58)

This invention relates to an auxiliary and detachable handle for shovels, forks and other handle-bearing tools.

In the use of shovels and other handle bearing tools now on the market, the user has to grasp a hand grip with one hand and then grasp the handle with the other hand at some place between the hand grip and the blade. Thus to scoop up a load of dirt or other material, the user must bend well over to carry out the operations of lifting and disposing of the load to one side. This is not only unduly tiring, but involves the necessary effort to raise the user's body to an erect discharging position. While it has heretofore been proposed to equip handle bearing tools, such as shovels and the like, with an auxiliary handle to lessen the effort in shoveling, these have not fully met the requirements of effective control of the tool and the load, in that some are too short to permit substantially erect shoveling, while all fail to so attach the auxiliary handle to allow complete positive control of the blade and its load in the erect position. Said positive control as afforded by the present invention thereby permits a pushing force on the blade, in addition to a pulling force, a direct rotational force and combinations thereof. Said control is exerted in such a manner as to allow the free universal action necessary to throw the load sideways, forward, backward, over-the-head, and combinations thereof.

It is an object of this invention to provide an improved auxiliary adjustable handle device for shovels, forks, and other handle bearing tools, having clamping members connected thereto, whereby the device may be adjustably mounted in desired positions on a handle of a shovel or like tool or which may, if desired, be permanently secured to such handles.

It is another object of the present invention to provide an improved auxiliary adjustable handle device for handle bearing tools having clamping members connected thereto whereby the device may be adjustably mounted on tool handles of varying sizes.

It is further an object of this invention to provide an improved auxiliary handle device for handle bearing tools whereby said auxiliary handle can be locked in place on the tool handle when said auxiliary handle is not in use.

A still further object of this invention is to provide an improved auxiliary handle device for shovels, forks, and other handle bearing tools that permit the user to load, lift or discharge at or from a level below his foot level while remaining in an upright position.

A still further object of the present invention is to provide an improved auxiliary handle device for handle bearing tools that permit direct universal control of the tool blade.

Other objects and many of the attendant advantages of this invention will be readily appreciated as the same becomes better understood by reference to the following detailed description when considered in connection with the accompanying drawing in which like reference numerals designate like parts throughout the figures thereof and wherein:

Fig. 1 represents a perspective of a spade shown with

2

a preferred embodiment of the present invention attached thereto.

Fig. 2 represents a side elevation of a spade with a preferred embodiment of the present invention attached thereto.

Fig. 3 is an enlarged elevated view of one embodiment of the clamp of the present invention, shown mounted on the regular handle of a spade with the latter being shown in cross section.

10 Fig. 4 is a plan view of the strap portion of the clamp.

Fig. 5 is an enlarged elevated view of another embodiment of the clamp of the present invention shown mounted on the regular handle of a spade with the latter being shown in cross section.

15 Fig. 6 is an enlarged front elevation of the handle of the present invention shown as removably secured to the spade handle.

Fig. 7 is a side elevation thereof.

20 Referring now to Fig. 1 of the drawing, there is shown a conventional spade, 11, a spade handle, 12, and a blade 13. The auxiliary handle includes an elongate arm 14 that connects the U-shaped offset handle portion 15, with a V-clamp member, 17. A grip member, 16, is press fitted on to one arm of the handle portion. A strap, 18, and nuts, 19, aid V-clamp or yoke, 17, to hold spade handle, 12. The phantom view of auxiliary handle, 14, illustrates the degree of lateral movability of said auxiliary handle.

25 Fig. 2 illustrates the relationship of the auxiliary handle and the spade handle, 12, of conventional spade, 11, when said auxiliary handle is secured to said spade handle by U-grip, 15. The U-shaped handle portion 15 has transverse portions adapted to extend on opposite sides of the spade handle 12. The offset portion 15 is inclined sufficiently to permit notched grip 16 to grasp spade handle, 12, as is shown in Fig. 2. The phantom view of auxiliary handle illustrates the degree of transverse movability of said auxiliary handle.

30 The V-clamp member or yoke, 17, is so shaped as to form substantially a wedge-shaped space in which the spade handle 12 may be seated. The strap 18 completes the triangular form to provide a three-point contact with the spade handle, 12, thereby permitting the clamp to be used on handles of varying sizes. The lower end of auxiliary handle is bent in a substantially circular shape and hooked to the central connecting portion of the V-clamp 17. The connecting portion, by virtue of the triangular configuration of the clamp, has clearance with the spade handle 12 conveniently to permit the auxiliary handle to be attached in this manner. Nuts, 19, screw on to threaded portions of V-clamp, 17, to hold strap, 18, against spade handle, 12. The strap, 18, as shown in Fig. 4, has elongated holes, 21, to facilitate adaptability of the clamp to varied size handles. However, it is understood that said holes may be made circular or rectangular.

35 The clamp 17 can be affixed to the spade handle 12 without requiring any structural alteration of the spade 11. However, if it is desired to fasten the auxiliary handle more rigidly and more permanently to the spade handle, 12, an eye bolt, 20, may be utilized by passing the shank of said eye bolt through a hole, 22, drilled through spade handle, 12. The lower portion of auxiliary handle is bent in a substantially circular shape and hooked into the eye of eye bolt, 20, which is contained by nut, 19.

40 Fig. 6, an enlarged view of the U-shaped handle portion 15, clearly illustrates same. Said handle portion 15 is formed in a substantially U-shape so as to permit the arms thereof to grasp the spade handle, 12. A circular notch, 23, in grip 16, provides a locking action. The bent form of said handle portion 15, as shown in Fig. 7,

provides the spring tension permitting it to securely grasp the spade handle, 12, when the former is not in use.

It can be readily seen from Fig. 1 that if a user were to grasp the spade handle, 12, at its upper portion, with one hand, and the grip 16, with the other, he would be able to scoop up a load while remaining in an upright position thereby eliminating the necessity of stooping. The auxiliary handle would also permit a user to reach down below his own foot level while the user was in a substantially erect position.

Rotation of the auxiliary handle about its own longitudinal axis, by means of handle portion 15, would cause rotation of the spade handle 12, and blade 13, due to the rotation of V-clamp, 17, and eye bolt 20, as shown in Fig. 3 and Fig. 5 respectively. Also a pushing force can be exerted on the spade through the auxiliary handle. The V-clamp, 17, and eye bolt, 20, in conjunction with auxiliary handle permit substantially universal movement of auxiliary handle and also afford direct control of the spade, 11, by the auxiliary handle.

It should be understood, of course, that the foregoing disclosure relates to only a preferred embodiment of the invention and that numerous modifications or alterations may be made therein without departing from the spirit and the scope of the invention set forth in the appended claims.

Having thus described the invention what is claimed is:

1. An auxiliary handle for use with a spade or the like, comprising an elongate arm having provisions at one end for pivotal attachment to the handle of a spade or the like, said arm having at the opposite end a laterally opening offset portion inclined to the length of the arm.

2. An auxiliary handle for use with a spade or the like, comprising an elongate resilient arm having provisions at one end for universal type connection to the handle of a spade or the like, said arm having its other end formed to provide a transverse offset portion in which the spade handle may extend, the offset portion being inclined to a straight line extending between the offset portion and the said provisions, and a grip member secured to the offset portion, the grip extending transversely of the arm.

3. An auxiliary handle for use with a spade or the like,

comprising an arm having provisions at one end for universal type connection to the handle of a spade, said arm being movable to a position in which it extends along the length of said spade handle, said arm having at its other

5 end a pair of spaced substantially parallel laterally extending portions adapted to extend respectively on opposite sides of said spade handle, a plane including said laterally extending portions being inclined to a line extending between said other end of said arm and said provisions.

10 4. An auxiliary handle for use with a spade or the like, comprising an arm having provisions at one end for universal type connection to the handle of a spade, said arm being movable to a position in which it extends along 15 the length of said spade handle, said arm having at its other end a pair of spaced substantially parallel laterally extending portions adapted to extend respectively on opposite sides of said spade handle, a plane including said laterally extending portions being inclined to a line extending between said other end of said arm and said provisions, and a grip secured to one of said laterally extending portions, said grip having a recess in which said spade handle may be seated.
